UNITED STATES PATENT OFFICE

2,690,499

VAPORIZER HEATING ELEMENT

Max Katzman, New York, N. Y.

Application July 10, 1952, Serial No. 298,145

1 Claim. (Cl. 219—40)

1

This invention relates to vaporizers and more particularly to heating elements used in conjunction therewith.

An object of this invention is to provide an economical, readily assembled vaporizer heating element.

Another object is to provide a ceramic cover for a vaporizer which will support the heating element and its accompanying parts.

Other objects of this invention will be apparent from the following description taken in connection with the drawing, in which

Figure 1 is a front plan view of my device partly cut away to reveal detail parts thereof;

Figure 2 is a bottom view of the parts shown in Figure 3; and

Figure 3 is a sectional view taken on lines 3—3 of Figure 2.

Referring specifically to the drawings, a vaporizer container 5 has a threaded neck 6 at its upper end which is engaged by the cover hold-down ring 7, to secure cover 8 in position with respect to the container 5. Between the neck 6 of the container 5 and cover 8, a ring washer 9 is positioned to provide a seal between these two members respectively. The cover 8 may be molded from ceramic material and has a spout 10 including a passage 19a in communication with the inside of the container 5, so that the vaporized medicant from the container 5 may discharge therethrough and into the atmosphere.

Additionally projecting from the cover 8 is bracket 11 which functions to guide and support the electrical connector (not shown) used in conjunction with this apparatus. The cover 8 is provided with a pair of holes through which the heating element terminals 12 and 13 project.

These terminals are fashioned with rounded tops and threaded lower portions inset from their main body portion and are spaced from the upper side of top cover 8 by washers 18 which engage the terminals at their inset portion. The threaded segments of terminals 12 and 13 engage heating electrodes 18 and 19 to support them and electrodes incasing member 16 in a manner hereinafter set forth.

Heating electrode incasing member 16 may be molded from ceramic or the like material and

2

incorporates a T-shaped slot 20 effectively surrounding the electrodes 18 and 19 on three sides. At the upper side of the points of the T are passages 21 and 22 through which threaded ends of terminals 12 and 13 project. The heating electrodes 18 and 19 are inverted L-shaped and are constructed from copper or any other electrically conductive material. The feet of the inverted L electrodes 18 and 19 engage the cross-member 10 of the T slot 20 of incasing member 16 and have terminals 12 and 13 threaded thereinto. Thus it may be noted that the terminals 12 and 13 support the heating electrodes and their incasing member 16 from the cover 8. A washer 17 and the ring washer 9 are situated between the cover 8 and the incasing member 16.

The lower portion of member 16 has a passage 25 included therein to insure free flow of the medicant around the heating elements.

20 I have described what I believe to be the best embodiments of my invention. I do not wish, however, to be confined to the embodiments shown, but what I desire to cover by Letters Patent is set forth in the appended claim.

25 I claim:

In combination with a vaporizer housing having a threaded neck portion, a disc-shaped cover for said vaporizer housing, a hold-down ring adapted to engage said cover and be threaded on the neck portion of said vaporizer housing, a pair of terminals seated on said cover and projecting therethrough, inverted L-shaped heating electrodes threaded on said terminals, an elongated T-shaped incasing member surrounding said electrodes on three sides, the feet portion of the electrodes being nestled in the cross portion of the incasing member, said construction and arrangement being such that the incasing member is supported by said electrodes, and a passage in the lower end of said incasing member.
